UNITED STATES PATENT OFFICE.

LADISLAV STASTNEY, OF CICERO ILLINOIS, ASSIGNOR TO WESTERN ELECTRIC COMPANY, INCORPORATED, OF NEW YORK, N. Y., A CORPORATION OF NEW YORK.

WIRE-DRAWING APPARATUS.

Application filed June 6, 1922, Serial No. 566,213. Renewed August 9, 1928.

This invention relates to improvements in wire drawing apparatus.

The object of the invention is to produce a wire drawing mechanism including a plurality of wire drawing units having a unitary driving mechanism, and means for operatively connecting and disconnecting each of said driving units therefrom, the said units and driving mechanism being so arranged that each of the units is readily accessible and at the same time the complete machine is compact and occupies a minimum amount of floor space. To this end the machine includes two series of wire drawing units mounted on a framework and arranged back to back, a common shaft being mounted in the framework between the two series of wire drawing units. Each of the wire drawing units includes a horizontal shaft driven from said common drive shaft, a cone capstan mounted thereon, a second horizontal shaft mounted above said capstan shaft and supporting a series of sheaves, a series of dies supported between the sheaves and capstan, together with a clutch mechanism associated with each capstan for operatively connecting and disconnecting said capstan to and from its associated drive shaft.

One of the features of the invention resides in an improved distributing mechanism for storing the wire on the take-up spool, the mechanism being so designed that it will accurately lay very fine wire, such as #40 B. & S. wire gauge, on a take-up spool in layers of closely adjacent coils without tangling the wire or intermingling the coils of one layer with that of the adjacent layers, the mechanism also being adjustable so as to both accommodate different lengths of take-up spool and to compensate for variations in the sizes of take-up spools due to inaccuracies in manufacture. Although this distributing mechanism is particularly well adapted for use in wire drawing machines, it is to be understood that it may be employed in various other machines for handling various different kinds of strands without departing from the spirit and scope of the present invention.

Another feature of the invention consists in providing the wire drawing machine with a mechanism for varying the speed of the take-up spool to compensate for the varying diameters thereof as wire is stored on the spool, and a connection between the driving mechanism for the take-up spool and the

driving mechanism for the improved form of distributing mechanism whereby the speed of the latter is synchronized with the varying speeds of the take-up spool.

Other objects and advantages of the invention will be set forth in the following description and particularly pointed out in the appended claims.

The drawings illustrate one embodiment of the invention, in which—

Fig. 1 is a front elevation of a machine embodying features of the invention;

Fig. 2 is a fragmentary horizontal section-al view taken on the line 2—2 of Fig. 1;

Fig. 3 is an enlarged fragmentary view in side elevation and partly in section illustrating the clutch mechanism mounted within the capstan;

Fig. 4 is an enlarged skeleton view partly broken away showing the mechanism for controlling the speed of the take-up spool;

Fig. 5 is an enlarged side elevation partly in section of the distributing mechanism;

Fig. 6 is a top plan view partly in section of the mechanism shown in Fig. 5;

Fig. 7 is an enlarged skeleton view, partly in section, showing the lever system of the distributing mechanism and illustrating the manner in which the said leverage mechanism may be adjusted to compensate for take-up spools of different lengths;

Fig. 8 is a detail view in horizontal section taken on the line 9—9 of Fig. 5;

Fig. 9 is an enlarged vertical sectional view showing in detail a portion of the mechanism shown in Fig. 4.

Referring now to the drawings in detail in which like reference numerals designate similar parts throughout the several views, 10 represents a framework which supports a plurality of compartments 5 of substantially rectangular shape each having top, bottom, back, and side walls. These compartments are arranged side by side to form two rows which are spaced apart by a compartment 15 extending between the rows. Each of the compartments 5 contains wire drawing apparatus which comprises a horizontal shaft 18, upon which is mounted a plurality of integral capstans 17—17 of different diameters. Supported above the shaft 18 are a plurality of sheaves 19 independently mounted upon a horizontally disposed shaft 20 suitably mounted within the compartment 5. Mounted between the sheaves 19 and capstans 17—17.

is a die block 21, also suitably supported within the compartment 5.

The capstans and other drawing elements contained within one row of compartments 5 face toward one side of the framework, while the capstans and drawing elements contained within the other row of compartments 5 face toward the opposite side of the framework. The front of each of the compartments 5 may be closed by sliding doors 100 and 101 of the type fully shown and described in a co-pending application of W. F. Hosford, Serial No. 566,206, filed June 6, 1922. When these doors are opened, complete access may be had to the drawing mechanism mounted within the compartment.

From the above it will be understood that the drawing apparatus mounted within one row of compartments 5 are accessible from one side of the machine, while the drawing apparatus mounted within the other row of compartments are accessible from the opposite side of the machine. In the machine illustrated in the drawings four compartments each containing individual wire drawing apparatus are mounted in each row, but it is to be understood that the number of these compartments in each row may be either increased or decreased without departing from the spirit and scope of the present invention.

The capstan shafts 18 of one row of capstans are mounted in alignment with the capstan shafts 18 of the other row of capstans 35 diametrically opposite, as shown in Fig. 2. Each of the capstan shafts 18 has secured thereto a bevel gear 32 which meshes with a bevel gear 33 at diametrically opposite points thereof. The gears 33 are mounted upon a shaft 34 rotatable within suitable bearings supported within the compartment 15. Secured to said shaft 34 is a sprocket 35 driven through a chain 36 by a sprocket 37 mounted upon an armature shaft 38 of an electric motor 39 supported by the framework 10 beneath the compartments 5. When it is desired to operate any of the wire drawing units the motor 39 is started and brought up to the desired speed through a suitable rheostat (not shown) controlled by an operating lever 201. Clutch mechanism, hereinafter to be described, is mounted within each of the capstans 17-17 and individual means is provided for actuating each of these 55 clutch mechanisms to connect or disconnect a capstan to or from its associated driving shaft 18.

Associated with each of the wire drawing apparatus mounted within the compartments 60 5 is a supply spool 50 (Fig. 1) containing wire to be reduced in diameter which is fed to the drawing mechanism by means hereinafter to be described, the drawn wire being stored on a take-up spool 61 driven by suitable mechanism, also to be described here-

inafter. The wire drawing apparatus mounted within each of the compartments 5 and the mechanism associated therewith for feeding and storing the wire constitute a unit and since all of the units are identical a detailed 70 description of one will suffice for all.

The supply of wire to be reduced in diameter is carried by a supply spool 50. The wire is guided from the supply spool over and under pulleys 51 and 52 respectively 75 (Fig. 1) and then over the rear sheave 19 and through the first reducing die 53 carried by the die block 21. The wire is then wound once around the capstan 17 of smallest diameter after which it is passed upward 80 and over the next sheave 19 and through the next reducing die 53 carried by the die block 21. The wire is then wound around the next capstan and then again over the next sheave 19 and through the next reducing die, 85 etc., etc., until it is finally drawn down to the desired diameter by the last reducing die. From the final reducing die the drawn wire passes around the capstan 17 of largest diameter and is guided by a pulley 57 mounted 90 on a stationary arm 58 adjustably positioned on the shaft 20. From the pulley 57 the wire passes through an opening in the closed doors 100 and 101 to a pulley 59 carried by an arm 60 and thence is led to a take-up spool 95 61 driven by mechanism hereinafter to be described.

The clutch mechanism for connecting the capstans 17-17 to and disconnecting them from the shaft 18 is illustrated in Fig. 2 of the drawings, the clutch being shown in its operated position. The shaft 18 is in the form of a sleeve which projects through a horizontally and centrally disposed opening made through the capstans 17-17 and carries adjacent its outer end (Fig. 3) an annular member 70 fast thereto which has secured to it by means of a pin 71 a plurality of clutch disks 72. Alternately mounted between the clutch disks 72 are clutch disks 73 which are secured by a pin 74 to the inner peripheral wall of a cup-shaped opening 75 made in the capstans 17-17. The disks 72 and 73 are movable longitudinally on the pins 71 and 74 respectively, and when pressure is exerted to force the disks together they form a driving connection between the capstans 17-17 and the sleeve 18, as is readily understood. Means for forcing the disks 72 and 73 together comprises a plate 76 which engages the outermost disk, and when the said plate is moved toward the right into the position shown, serves to force the disks together sufficiently to cause them to rotate as a unit. The plate 76 is fastened to one end of a shaft 77 mounted within the sleeve 18. A transverse pin 79 is secured to the shaft 77 and projects through diametrically opposite longitudinal slots 80 made in the sleeve 18 and is suitably connected with a housing 78 so as 130

to be movable therewith and free to rotate independently of the said housing. Through the medium of the pin 79 and slots 80 the shaft 77 and housing 78 are movable together longitudinally of the sleeve 18. Means (not shown) is provided for preventing the housing from turning but permitting it to move longitudinally of the sleeve 18. Secured to the sides of the housing 78 at diametrically opposite points are pins 81 which receive the bifurcated ends of a forked member 82 which is pivoted at 83 to a link 84. The link has secured to its free end a pin 85 which fits within a slot formed in the end of a vertically reciprocable rod 86. For a more detailed illustration and description of the clutch mechanism per se reference is made to the co-pending application of W. F. Hosford, Serial No. 566,206, filed June 6, 1922.

When it is desired to release the clutch mechanism and stop the operation of the capstans 17—17 a knob 125 is operated which, through suitable mechanism, lifts the rod 86 to disengage the clutch disks 72 and 73. When it is desired to start the capstans a foot pedal 97 is depressed which, through suitable mechanism, moves the rod 86 downwardly to force the clutch disks 72 and 73 together so that they constitute a driving connection between the capstans 17—17 and the shaft 18 (Fig. 1). For a detailed disclosure of the mechanism controlled by the knob 125 and foot pedal 97 for raising and lowering the rod 86 to engage and disengage the clutch mechanism, reference is made to Patent 1,608,248, issued November 23, 1926 to J. N. Selvig. A detailed disclosure and description of this mechanism is omitted from this application for the sake of simplicity, since a full disclosure and description thereof is not essential to a complete understanding of the present invention.

In wire drawing machines the former practice has been to connect the capstan by intermediate shafting to a clutch mechanism mounted apart therefrom. By mounting the clutch mechanism within the capstan this intermediate shafting is dispensed with, resulting in a conservation of power and permitting higher speed operation. Furthermore, the capstan provides a housing for the clutch mechanism and since both the capstan and clutch mechanism only occupy the space necessary for the capstan alone, the over-all width of the machine is materially reduced and a saving of considerable floor space effected.

The mechanism for driving the take-up spool 61 at varying speeds to compensate for the varying diameters thereof as wire is stored on the spool, which mechanism includes a friction clutch the driving action of which is controlled by the tension of the drawn wire, will now be described.

Meshing with a gear 90 rotatable with the

capstans 17—17 is a gear 38 (Figs. 3 and 4) which drives a pinion 39 secured on a horizontal shaft 40 positioned a short distance below the shaft 18. The shaft 40 extends into a housing 41 (Fig. 1) and carries at its forward end a worm gear 42 (Fig. 4) which meshes with a worm 43 formed on a sleeve 45 rotatable in suitable bearings (not shown) carried by the housing 41. One end of the sleeve has secured thereto a disk clutch member 48. Extending through the sleeve 45 and rotatable independently thereof is a spindle 152 having splined thereon a clutch disk member 54. The take-up spool 61 is suitably secured to the spindle 152 so as to rotate therewith. The clutch disks 48 and 54 are normally held out of engagement with each other by means of a spring 59, which is a compression spring, one end of the spring pressing against the shaft secured to the clutch disc 48 and the other end of the spring pressing against the end of the sleeve secured to the clutch disc 54. When the disks are in engagement they form a driving connection between the sleeve 45 and shaft 152 so that the take-up spool 61 is driven by the shaft 40. The driving engagement of the disks 48 and 54 is controlled by suitable leverage mechanism indicated generally by reference numeral 200. This mechanism includes the arm 60 having pivotally mounted thereon the pulley 59 over which the drawn wire passes to the take-up spool 61. For a detailed disclosure and description of the mode of operation of the leverage mechanism 200 to vary the speed of the take-up spool 61 responsive to the tension on the drawn wire between the take-up spool and last reducing die, reference is made to Patent 1,598,937, issued September 7, 1926 to J. N. Selvig, since this mechanism is identical with that disclosed in the patent above referred to.

Briefly described, this mechanism operates as follows:

In the operation of the wire drawing machine the capstans 17—17 deliver the wire to the take-up spool 61 at a constant speed, and the speed at which the wire may be drawn through the dies is dependent upon the speed that the wire may be taken up. To take up the wire successfully at a high speed the tension on the wire must be maintained substantially constant. In starting and stopping the machine and during the spooling of the wire the tension on the wire will vary momentarily. During the spooling of the wire the diameter of the take-up spool increases as each layer is wound thereon, and in a case where the dies are delivering drawn wire at the rate of approximately 2500 feet per minute, the take-up spool must be driven at speeds varying from 5000 to 10,000 R. P. M. in order to compensate for the varying diameters of the take-up spool and maintain a constant tension on the wire to insure uni-

form spooling thereof on the take-up spool. When the tension upon the wire is increased above the proper tension during spooling, the free end of the lever 60 will be moved down. 5 This lever in its movement causes a link 301 to be moved upwardly, placing under compression a spring 302 mounted about the link 301. The spring 302 upon being compressed lifts a housing 303. This housing has integral therewith a pair of annular collars which form between them an annular groove 304 within which is mounted an eye formed upon the end of a lever 305. This lever is fixed to a shaft 306 upon which its also secured 10 an arm 307 which is attached to the upper end of a link 308, the lower end of which is pivoted to an arm 309 pivoted in turn to a lever 310. As the housing 303 moves upwardly through the lever 305, arm 307, link 308, and arm 309, the lever 310 is moved clockwise relieving the compression on a spring 311 which normally tends to urge the friction disks 54 and 48 into close engagement with each other, and thus relieving the pressure 15 between said disks, thereby reducing the driving effect of the driving disk 48, resulting in a reduction in speed of the take-up spool shaft 152.

When the tension on the wire is decreased below the proper tension, the lever 60 moves upward, due to a slack in the wire, which results in a reverse operation of the mechanism just described which causes a closer engagement of the clutch disks 54 and 48 to 20 drive the take-up spool. From this it will be understood that as the tension on the wire between the capstan 17 and the take-up spool varies, the pressure between the clutch members 48 and 54 will vary in response thereto 25 causing a change in the speed of the take-up spool accordingly. Due to the change in pressure of the members 48 and 54 in response to the tension in the wire, a substantially constant tension is maintained on the wire.

40 The distributing mechanism for laying the wire on the take-up spool comprises two parallel fingers 205 between which the drawn wire passes to the take-up spool 61 (Figs. 6 and 7). These fingers are secured to a head 206 which is held within a cup-shaped housing 207 by means of a sleeve 208. The housing 207 is pivoted to an arm 209 so as to be adjustable in a vertical plane. The arm 209 is integral with a block 210 internally screw 45 threaded to receive a screw 211 carried by a bracket 212 pinned to a reciprocable rod 213. As this rod is reciprocated, by a mechanism hereinafter to be described, through the bracket 212, the fingers 205 are moved back and forth across the take-up spool 61.

50 The means for reciprocating the rod 213 comprises a pinion 214 fast on the take-up spool spindle 152 which meshes with a gear 215 fast upon a shaft 216 mounted within 55 suitable bearings within the casing 41. Also

fast on the shaft 216 is a worm 217 which meshes with a worm gear 218 secured to a shaft 219. A gear 220 is also secured to the shaft 219 which drives an idler 221 rotatable on a stud shaft 222 carried by a bracket 223. 70 The idler 221 meshes with a gear 224 fast upon a shaft 225 which also has secured to it a cam 226. Cooperating with the said cam are anti-friction rollers 227 and 228 carried by a rod 229 reciprocably mounted within 75 suitable bearings carried by the housing 41. Pivoted to the rod 229 at a point 230 is a lever 231 the upper end of which has a bifurcated portion 232 which straddles a pin 233 fast to the reciprocable rod 213. The lower end of 80 the lever 231 fits within an eye 234 (Fig. 8) which has secured to it a pin 235 pivotally mounted within a bracket 236 threaded upon a screw 237. As the take-up spool spindle 152 is driven at varying speeds through the 85 friction driving mechanism shown in Fig. 4, the cam 226 is rotated in synchronism therewith through the train of gears comprising pinion 214, gear 215, worm 217, worm gear 218, gears 220, 221, and 224. As the cam 90 226 revolves, it engages rollers 227 and 228, alternately causing the rod 229 to be reciprocated. This movement of the rod 229 causes a similar movement of the rod 213 through the arm 231. The reciprocation of 95 the rod 213, as previously described, moves the fingers 205 back and forth across the take-up spool.

The length of the reciprocations of the rod 213 to accommodate different lengths of 100 take-up spools is controlled by turning screw 237 clockwise or counter-clockwise by means of a serrated knob 238, which serves to raise or lower the bracket 236, as viewed in Fig. 5, to which the pivotal point of the link 231 is 105 secured, and thereby lengthen or shorten the arc through which the upper end of the said lever moves, which, of course, controls the length of reciprocation of the rod 213. When this adjustment has been made for spools of 110 a given length and it is found, due to inaccuracies of manufacture, that a spool will not occupy the correct position on spindle 152, these inaccuracies may be compensated for by adjusting the position of the fingers 115 205 relative to the bracket 212 by turning the screw 211 clockwise or counter-clockwise by means of a serrated knob 239 attached thereto.

In order to lay the wire on the take-up 120 spool in close adjacent coils in each layer it is necessary to reciprocate the rod 213 at different speeds, dependent upon the diameter of the wire to be stored. The speed of reciprocations of the rod 213 is adjusted by 125 substituting gears of different diameters and numbers of teeth for the gear 224. For this reason the bracket 223, upon which the idler gear 221 is rotatably supported, is adjustable so that the gear 221 may be lowered 130

or raised as a gear having a smaller or larger diameter than the gear 224 is used. The bracket 223 is locked in its adjusted position by means of fixed screws 240 which fit within slots 241 cut in the bracket 223.

Since the distributing mechanism is driven from the take-up spool spindle, as this spindle is varied in speed by the friction driving mechanism shown in Fig. 4, the speed of the entire distributing mechanism is correspondingly varied so that it is always in complete synchronism with the rotations of the take-up spool.

What is claimed is:

- 15 1. In a wire drawing apparatus, a multiple series of wire drawing units back to back, comprising a base, a top section providing a plurality of wire drawing compartments mounted on said base, each of said compartments enclosing wire drawing mechanism including two shafts, one mounted above the other, a series of sheaves revolvably mounted on one of said shafts, a cone capstan mounted on the other shaft, and a series of dies, a common drive shaft, a shaft for each of said capstans operatively connected with said common drive shaft, and a clutch mechanism associated with each of said capstans for connecting and disconnecting it to and from engagement with its associated drive shaft.
- 20 2. In a wire drawing apparatus, a multiple series of wire drawing units back to back, comprising a base, a top section providing a plurality of wire drawing compartments supported by said base, means for permitting unobstructed access to each of said compartments, each of said compartments enclosing wire drawing mechanism including two shafts positioned in the same vertical plane, a
- 25 series of sheaves revolvably mounted on one of said shafts, a cone capstan mounted on the other shaft, a series of dies, a common drive shaft disposed at right angles to the capstan shafts, a shaft for each of said capstans operatively connected with said common drive shaft, and a clutch mechanism associated with each of said capstans for connecting and disconnecting it to and from engagement with its associated drive shaft.
- 30 3. In a wire drawing machine, a multiple series of wire drawing units back to back, comprising a base, a top section providing a plurality of wire drawing compartments mounted on said base, each of said compartments enclosing separate and distinct wire drawing mechanism including two shafts, one mounted above the other, a series of sheaves mounted on one of the shafts, a capstan mounted on the other shaft, and a series of dies supported between the sheaves and capstan, a common drive shaft located between and in the rear of said compartments, a shaft for each capstan operatively connected with said drive shaft, and a clutch mechanism associated with each of said capstans for connecting and disconnecting them to and from their associated drive shaft.
- 35 4. In a wire drawing machine, a multiple series of wire drawing units back to back, comprising a base, a top section providing a plurality of wire drawing compartments mounted on said base, each of said compartments enclosing separate and distinct wire drawing mechanism including two shafts, one mounted above the other, a series of sheaves mounted on one of the shafts, a capstan mounted on the other shaft, and a series of dies supported between the sheaves and capstan, a common drive shaft located between and in the rear of said compartments, a shaft for each capstan operatively connected with said drive shaft, and a clutch mechanism associated with each of said capstans for connecting and disconnecting them to and from their associated drive shaft.
- 40 5. In a wire drawing apparatus, a multiple series of wire drawing units back to back, comprising a base, a top section providing a plurality of wire drawing compartments supported by said base, a pair of slidable doors mounted to close the front of the compartment, each of said compartments enclosing wire drawing mechanism including two shafts positioned in the same vertical plane, a
- 45 series of sheaves revolvably mounted on one of said shafts, a cone capstan mounted on the other shaft, a series of dies, a common drive shaft disposed at right angles to the capstan shafts, a shaft for each of said capstans operatively connected with said common drive shaft, and a clutch mechanism associated with each of said capstans for connecting and disconnecting it to and from engagement with its associated drive shaft.
- 50 6. In a wire drawing apparatus, a multiple series of wire drawing units back to back, comprising a base, a top section providing a plurality of wire drawing compartments mounted on said base, each of said compartments enclosing separate and distinct wire drawing mechanism including two shafts, one mounted above the other, a series of sheaves mounted on one of the shafts, a capstan mounted on the other shaft, and a series of dies supported between the sheaves and capstan, a common drive shaft located between and in the rear of said compartments, a shaft for each capstan operatively connected with said drive shaft, and a clutch mechanism associated with each of said capstans for connecting and disconnecting them to and from their associated drive shaft.

ments enclosing separate and distinct wire drawing mechanism including two shafts, one mounted above the other, a series of sheaves mounted on one of the shafts, a capstan mounted on the other shaft, and a series of dies supported between the sheaves and capstan, a common drive shaft located between and in the rear of said compartments a shaft for each capstan operatively connected with said drive shaft, and a clutch mechanism associated with each of said capstans to operatively connect them to and from their associated drive shaft.

4. In a wire drawing machine, a multiple series of wire drawing units back to back, comprising a base, a top section providing a plurality of wire drawing compartments mounted on said base, each of said compartments enclosing separate and distinct wire drawing mechanism including two shafts, one mounted above the other, a series of sheaves mounted on one of the shafts, a capstan mounted on the other shaft, and a series of dies supported between the sheaves and capstan, a common drive shaft located between and in the rear of said compartments, a shaft for each capstan operatively connected with said drive shaft, and a clutch mechanism associated with each of said capstans for connecting and disconnecting them to and from their associated drive shaft.

5. In a wire drawing apparatus, a multiple series of wire drawing units back to back, comprising a base, a top section providing a plurality of wire drawing compartments supported by said base, a pair of slidable doors mounted to close the front of the compartment, each of said compartments enclosing wire drawing mechanism including two shafts positioned in the same vertical plane, a series of sheaves revolvably mounted on one of said shafts, a cone capstan mounted on the other shaft, a series of dies, a common drive shaft disposed at right angles to the capstan shafts, a shaft for each of said capstans operatively connected with said common drive shaft, and a clutch mechanism associated with each of said capstans for connecting and disconnecting it to and from engagement with its associated drive shaft.

In witness whereof, I hereunto subscribe my name this 31st day of May A. D., 1922.

LADISLAV STASTNEY.
